CONTAINER CLOSURE OR THE LIKE

Nicholas D. Comisso, Victor, Donald A. Haase, Penfield, and Paul H. Nielsen, Rochester, N.Y., assignors to Mobil Oil Corporation

Filed July 14, 1972, Ser. No. 271,865

Term of patent 14 years

Int. Cl. D9—07

U.S. Cl. D9—254

FIG. 1

FIG. 3

FIG. 1 is a top plan view of a container closure or the like showing our new design;

FIG. 2 is a side elevational view; and

FIG. 3 is a cross-sectional view taken along line 3—3 of FIG. 1.

We claim:

The ornamental design for a container closure or the like, substantially as shown and described.
